cheap, and, therefore, a preferred granular material, but it is to be understood that any other granular or comminuted material is within the scope of the present invention and that the material may be introduced into the tubes in any manner to result in substantial uniformity.

Upon the granular material now occupying a position in the bottom of the tube sections a cementitious material is introduced. This may also vary greatly according to circumstances, but a silicate compound has been found to serve the purpose admirably, and is, therefore, suggested as the preferred cement. This may be introduced into the tube sections upon and to impregnate the contained granular material in any manner found convenient.

At Figure 4, the reservoir 16 is shown having a flexible tube 17 connected therewith, and adapted to drain the contents of the reservoir. It is found convenient in the use of this device to support or suspend the reservoir in any approved manner and to manually trace along each row of tube sections with the end of the flexible tube 17 discharging the cementitious material into the tube sections. With some experience of the operator, this may be done with great uniformity. After the cementitious material has hardened, it will be found to have impregnated the granular material and therewith to have formed a rigid closure for the lower ends of the tube sections.

The next step is the introduction of the explosive or detonating material. This may also be done in any approved manner, but for convenience and speed a device, such as shown at Figure 3, is preferably employed. This comprises a rod 18 having extending therefrom a plurality of arms 19, each of which is provided at its end with a spoon 20 of the capacity required to supply the desired explosive or detonating charge. The device is employed by dipping the spoons simultaneously into a mound of the detonating or

explosive material, moving it over a row of the tubes, then tilting the structure to discharge the material simultaneously from all of the spoons into the open upper ends of the tube sections. It is obvious that for speed the number of spoons should correspond exactly to the number of tube sections in a row.

After the introduction of the explosive or detonating charge, the operator again applies a cementitious material to the top. This may be done by employing the device shown at Figure 4, and in the same manner previously outlined. The hardening of this cementitious material completes the article in accordance with the present method. Of course, the article when so completed may be further employed by coating or covering in any manner. If the device as an entirety is to be used as a salute instead of a torpedo, then before introducing the last cementitious coating, a fuse section is introduced into each tube section and cemented therein by the last application of the cementitious material.

I claim:

The method of producing an explosive article consisting in arranging a plurality of rows of constrained open ended tube sections separating said rows by separating strips, sifting granular material over the top of the tube sections to enter therein and fall to the bottom of said sections, introducing a cementitious material onto the granular material by directing a stream along each row serially whereby upon hardening the granular and cementitious material forms a cap for one end of the tube, introducing upon the hardened cementitious material a charge simultaneously into each section of a row, and completing by serially directing cementitious material upon the tops of the charges to close the tops of the tube sections.
